William R. Park

UNITED STATES PATENT OFFICE.

WILLIAM R. PARK, OF TAUNTON, MASSACHUSETTS.

INJECTOR.

SPECIFICATION forming part of Letters Patent No. 448,488, dated March 17, 1891.

Application filed September 9, 1887. Serial No. 249,269. (Model.)

To all whom it may concern:

Be it known that I, WILLIAM R. PARK, of Taunton, in the county of Bristol and State of Massachusetts, have invented an Improved 5 Jet Apparatus, of which the following is a specification, reference being had to the accompanying drawings, in which—

Figure 1 is a lengthwise section showing the main features of my improved apparatus. 10 Fig. 2 is a section on line $\alpha\alpha$ of Fig. 1, and Fig. 3 is a section on line $z\alpha$ of Fig. 1.

In my patent, No. 352,980, dated November 23, 1886, I have described a jet apparatus consisting of two steam-nozzles, each having 15 its combining and delivery tubes and an overflow-chamber communicating with the second combining-tube by an opening or openings through the walls of that tube. In my present invention it is essential to establish a jet 20 through the combining and delivery tubes independent of the steam-nozzles of those tubes—that is to say, in my former apparatus the steam flowing through the steam-nozzles was what established the jet through the 25 combining and delivery tubes of those steam-nozzles; but in my present apparatus I establish the jet through the combining and delivery tubes a moment before the steam is admitted to the steam-nozzles, so that when the 30 steam is admitted to the steam-nozzles it is not required to establish the jet, but simply to maintain and increase the force of a jet already established, as will be more clear from the following description of that form 35 of my apparatus shown in the drawings.

D is one of the steam-nozzles, d its combining-tube, and d' its delivery-tube. The holes d^2 are the regulating-holes described in my patent above referred to.

40 A is the water-inlet through which water is supplied to the water-chamber α .

F is the other steam-nozzle, and f its combining and delivery tube, the steam-nozzle F being formed in the apparatus shown in the 45 drawings by the projection of the tube d' into the enlarged mouth of the tube f .

The overflow-chamber 8 is provided with a jet apparatus 4 5 and a cock 6 7, and by means of this jet apparatus and cock a current of 50 water can be established from water-chamber α through tubes $d d' f$ without the aid of the steam-nozzle D F, which, as I have before said,

is one feature of my present invention. After this current has been established the steam is admitted to nozzles D F, thereby maintaining and greatly quickening that current, so that when cock 6 7 is closed the jet or current through $d d' f$ has force enough to open valve 9 and force its way into the boiler, the apparatus being piped to the boiler in the usual 60 way, as will be plain to all skilled in the art without further description. 55

In the apparatus described in my former patent it was necessary to have one or more openings through the walls of tube f , communicating with the overflow-chamber 8, and consequently the overflow-chamber became a vacuum-chamber after the jet was established through tube f ; but in my present apparatus, when the jet apparatus 4 5 is used, 70 the first result is to establish a partial vacuum in chamber 8, and consequently the air-pressure upon the water in the well or tank forces the water up through inlet A into water-chamber α , thus establishing a jet through $d d' f$ 75 into chamber 8 and out of chamber 8 through tube 5 and cock 6 7, and steam is not admitted to nozzles D F until after this current or jet is established. Moreover, as soon as steam is admitted to nozzles D F and the cock 6 7 80 closed the chamber 8 becomes full of water under pressure, the pressure being enough greater than the boiler-pressure to open valve 9 and cause the water to enter the boiler.

The apparatus shown in the drawings is intended for use where the water-level in the tank or well is considerably below the apparatus—that is, where the water requires to be forced by atmospheric pressure through inlet A into water-chamber α —and its operation is as 85 follows: The steam-inlet 1 is piped to the boiler, so that when valve 3 is open the steam will flow through inlet 1, lifting valve 2 and flowing through pipe 10, valve 3, nozzle 4, tube 5, and through outlet 6 of cock 7, thus forming 90 a partial vacuum in chamber 8 and causing the atmospheric pressure on the water in the tank or well to establish a current from water-chamber α through tubes $d d' f$, as before described. Valve 11 is then opened and the 100 steam flows through steam-inlet B and passages $b b'$ and supplies nozzles D F, thereby maintaining and quickening the jet already established through $d d' f$. Cock 7 is then 95

turned, closing outlet 6, and the jet through *f* instantly fills chamber 8 and causes pressure in that chamber sufficient to open valve 9 and supply the boiler. Valve 3 should of course be closed after valve 11 is opened; but in case it is not (and, as will be clear, it is immaterial, for valve 3 is used as a positive shut-off valve) the valve 2 acts to prevent any flow of water from chamber 8 through nozzle 4, past valve 3, and through pipe 10, for the pressure in chamber 8 is greater than the boiler-pressure when the apparatus is feeding the boiler, and therefore the pressure tending to close valve 2 is greater than the steam-pressure tending to open it. It will of course be clear that the various valves and cocks may be so connected as to be opened in proper order by the movement of a single handle or lever, and it will also be obvious that the jet apparatus 4 5 will be unnecessary when the chamber *a* is supplied with water from an elevated tank, so that the jet can be established through *d d' f* by simply opening cock 6 7; but as such a head of water is not always available I have shown well-known means for establishing a jet through *d d' f*.

In practice the casting which supports valve 9 (shown in section in Fig. 3) should be made in two pieces for convenience in putting tube *f* into place, as will be clear to all skilled in the art.

I am aware of Little's patents, No. 272,448, dated February 20, 1883, and No. 307,784, dated November 11, 1884; Felthousen and Volker's patent, No. 283,229, dated August 14, 1883, and Colvin's patent, No. 303,986, dated August 26, 1884, and disclaim all that is shown in them.

While it is not new to use two steam-jets, each having its combining and delivery tube and each having its overflow-chamber, (see

Patent No. 283,229,) yet I am the first, so far as I am aware, to use a steam-jet with a combining and delivery tube discharging directly into the combining and delivery tube of a 45 second steam-jet which discharges into a single overflow-chamber, into which the mixed water and steam from both the steam-jets and from the combining and delivery tube of the first steam-jet are forced directly through 50 the tube of the second jet. This new principle of construction results in decided advantages which cannot be obtained where the mixed water and steam of the first steam-jet and its combining and delivery tube is forced 55 into an overflow-chamber, from which overflow-chamber the water mixed with steam (passed through the combining and delivery tube of the first jet) enters the combining and delivery tube of the second jet, as in Patent No. 283,229, which, as before stated, has, in fact, two independent overflow-chambers, one for the first steam-jet and its tube and the other for the second steam-jet and its tube. 60

What I claim as my invention is—

1. In combination with overflow-chamber 8 and its waste-cock 6 7, two steam-nozzles 10 and F, with their tubes *d d' f*, nozzle D and its tube *d d'* emptying directly through nozzle F into its tube *f*, and tube *f* emptying directly into chamber 8, all substantially as described. 65

2. In a jet apparatus having an auxiliary lifting-jet, the automatic valve 2, exposed on one side to steam-pressure and on the other side to water-pressure, substantially as and for the purpose specified. 70
